(57) CLAIM

The ornamental design for a boot, as shown and described.

DESCRIPTION

FIG. 1 is a rear perspective view of a boot showing my new design;

FIG. 2 is a rear side view thereof;

FIG. 3 is a right side view thereof;

FIG. 4 is a left side view thereof; and,

FIG. 5 is a rear perspective view of a second embodiment of the boot shown in FIG. 1.

The broken lines showing the heel, upper, zipper, zipper pull, and studs (in the case of FIG. 5) is for illustrative purposes only and forms no part of the claimed design. The sole of the shoe is plain and unornamented.
